ATTORNEY

UNITED STATES PATENT OFFICE.

FRANCIS J. MCGRADY, OF NEW YORK, N. Y.

SLEEPING-CAR.

SPECIFICATION forming part of Letters Patent No. 245,085, dated August 2, 1881.

Application filed May 6, 1881. (No model.)

To all whom it may concern:

Be it known that I, FRANCIS J. MCGRADY, of the city, county, and State of New York, have invented certain new and useful Improvements in Sleeping-Cars, of which the following is a specification.

The object of this invention is to improve the sleeping-cars at present in use in such a manner that they can be made more comfortable to travelers; and the invention consists in a sleeping-car compartment having seats and backs divided into wider and narrower portions, the wider portions, adjoining the windows, being adapted to be converted into a berth, while the narrower portions, at the inner walls, are retained as seats for use in dressing and undressing, said compartment being provided with ventilating sliding doors and double inner walls in which the doors move.

The invention consists, further, in a closed compartment divided into wider and narrower portions, the wider portions, adjoining the windows, being adapted to be converted into a berth, while the narrower portions, at the inner walls, are retained as seats for use in dressing and undressing, said compartment being provided with ventilating sliding doors below, a wide removable upper berth, and sliding doors opposite said berth.

In the accompanying drawings, Figure 1 represents a perspective view of my improved sleeping-car with parts broken out, and Fig. 2 is a sectional plan view of the same.

Similar letters of reference indicate corresponding parts.

By reference to the drawings, A represents a section of a sleeping-car which is formed by permanent transverse side walls, B, that extend up to the roof of the car, and by inner walls, C, which run along the seats, and which are also, like the side walls, extended to the roof.

The inner walls, C, are double, and are arranged with sliding doors C' for the lower and C² for the upper berth of the section, the upper doors being preferably guided by hangers upon suitable rails, while the lower doors slide in the double walls and are provided with slats for ventilation.

The sleeping-car may be arranged either wholly or partly with these compartments. In

the latter case the remaining portion of the car is arranged in the common manner, as at present. A few of the compartments may be arranged without upper berths, in which case the lower sliding doors are continued through without being divided.

The seats D and backs E of each section are divided into two parts, of which the larger parts, being about two-thirds or more of the seats and backs next to the window, are used for forming the berth proper, while the remaining parts, adjoining the door, are retained as seats when the berth is made up. This has the advantage that the occupant or occupants may dress and undress at the inside of the section, being fully inclosed by the doors, and without being observed from the outside, securing thereby full privacy, which is frequently greatly desired, as in the case of ladies, invalids, &c.

In compartments where there are only lower berths the seats for dressing and undressing may be arranged above the berth by means of hinged panels, which fold into the walls and can be lowered for use and raised again after use.

By dividing the seats and backs in the manner described and providing the section with sliding doors, more comfortable berths, and especially more convenient lower berths, are obtained and a greater privacy secured.

By means of the sliding doors a closed compartment can be formed during the day, if desired.

Having thus described my invention, I claim as new and desire to secure by Letters Patent—

1. A sleeping-car compartment having seats and backs divided into wider and narrower portions, the wider portions, adjoining the windows, being adapted to be converted into a berth, while the narrower portions, at the inner walls, are retained as seats, said compartment being provided with ventilating sliding doors and double inner walls in which the doors move, substantially as described.

2. A sleeping-car compartment having seats and backs divided into wider and narrower portions, the wider portions next, the windows, being adapted to be converted into a berth, while the narrower portions, at the inner walls, are retained as seats for use in dressing

and undressing, said compartment being provided with ventilating sliding doors below, a wide convertible upper berth dividing the compartment horizontally, and sliding pendent doors opposite said upper berth, substantially as described.

5 In testimony that I claim the foregoing as

my invention I have signed my name, in presence of two witnesses, this 16th day of April, 1881.

FRANCIS J. McGRADY.

Witnesses:
